UNITED STATES PATENT OFFICE

108,911

DESIGN FOR A VENTILATOR FOR GAS STOVES OR THE LIKE

Frederick A. Kell, St. Louis, Mo., assignor to Hull-Dobbs Enterprises, Akron, Ohio, a corporation of Ohio

Application October 4, 1937, Serial No. 71,959

Term of patent 14 years

To all whom it may concern:

Be it known that I, Frederick A. Kell, a citizen of the United States of America, residing at St. Louis, in the county of St. Louis and State of Missouri, have invented a new, original, and ornamental Design for Ventilators for Gas Stoves or the Like, of which the following is a specification, reference being had to the accompanying drawing, forming a part hereof.

The figure is a perspective view of a ventilator

for gas stoves or the like showing my new design.

The opposite ends of the ventilator are of substantially identical design.

I claim:

The ornamental design for a ventilator for gas stoves or the like, substantially as shown and described.

FREDERICK A. KELL,
